Attorney

UNITED STATES PATENT OFFICE.

JESSE L. CARRIGAN, OF BIRMINGHAM, ALABAMA.

SCREEN ADJUSTER.

Application filed January 22, 1926. Serial No. 83,076.

- My invention relates to window screens, and is more particularly concerned with the ready and convenient manner of adjusting the spring mounted shoes or guides which the screen carries at one side to cause same to engage or disengage the rail in the sash frame on which they slide and thus permit the screen to be easily and quickly mounted or dismounted.
- 10 In sliding window screens of the type in general use each adjustable shoe or guide has been set against the rail by means of a screw which is run through the side of the screen frame and engages under the spring opposite the shoe, thus acting to force the shoe outwardly against the rail of the frame. These screws are the source of much trouble in the removal and replacement of the screens; they are difficult to be handled by 20 women; they require more or less skilled labor for the proper adjusting and setting of the screens; and the manipulation of the screws causes frequent damage to the screen wire opposite them.
- 25 The object of my invention is to devise a very simple means readily accessible and capable of quick and positive action which will set the shoe with the desired compression against the sash frame rail so as to readily clamp the screen in position and which may be with the greatest ease thrown out of operating position to release the screen and permit of its removal from the window frame.
- 30 More particularly my invention consists in interposing behind the spring support for each shoe a cam having a plurality of flat faces which is adapted to be operated by a handle or any suitable instrument applied from the front of the screen inside of the window. The flattened faces enable the cam to hold the shoe interlocked with the frame rail at intermediate positions.
- 35 My invention further comprises the novel details of construction and arrangements of parts, which in their preferred embodiment only are illustrated in the accompanying drawings, in which:—
- 40 Fig. 1 shows a horizontal cross-section through a sash with a screen mounted in position.
- 45 Fig. 2 is a vertical cross-sectional view taken on the line 2—2 of Fig. 1, with the
- screen frame broken away to show the shoe controlling cam in elevation.
- 50 Similar reference numerals refer to similar parts throughout the drawings.
- 55 In the embodiment of my invention illustrated, I show the casing 1 on the window frame 2, the casing having vertical rails or runners 3 adapted to receive the window screen which comprises side frame members 4, one of which is recessed at 5 to form a guide for the rail 3 at the other side of the window. The usual type of springs 6 are mounted in the recess 5 and the inside edge of the recess 6 is reduced in width so that by shifting the screen to the right, Fig. 1, it will be free to pass the rail 3 that normally engages in the recess 6. In Fig. 70 60 65 70 75 80 85 90 95 100 105
- 2 I show the type of spring means in the recess 6 for engaging its respective rail 3, each means comprising a flat spring 9 which is secured to the inner wall 8 of the recess 6 by means of screws or pins 10 which engage in elongated slots in the ends of the springs. At its center the spring 9 carries a shoe 11 which is shaped and adapted to engage the rail 3 and has tongues 10 which mount it on the spring. Behind the spring and partly in a recess 12 formed in the screen wall 8 I mount a polygonal cam 13 upon an operating shaft 14 which extends through the inside face of the screen side 4 so as to be accessible from within the house for manipulation. Preferably, the exposed side of this shaft is slotted to provide for the engagement therewith of a screwdriver so that the cam can be shifted to force the shoe outward against the rail 3 or to leave it free to spring back from the rail. Any other suitable means to manipulate the cam may be provided. The cam is provided with any desired number of flat faces so that it can be set to various adjusted operating positions and in these various positions it will set the shoe to accommodate the varying widths between the rails 3 in the window.
- In operation, it is only necessary to turn the cam to set its shortest radius face against the shoe to cause the latter to release its respective rail 3, whereupon by shifting the whole frame to the right (Fig. 2), against the action of the springs 7, the screen can be removed. When the screen

has been reset in position, by rotating this cam until the shoe is positively forced by a longer radius face against the rail 3 the screen will be again quickly and effectively locked in operating position.

The cheapness of construction and the extreme simplicity of operation are the features which I expressly wish to emphasize in connection with my present invention.

10 Having thus described my invention, what I claim as new and desire to secure by Letters Patent, is:—

In a window screen having side grooves and spring rail engaging elements mounted

therein part of which carry shoes, of an 15 adjusting means for the spring elements carrying shoes comprising for each such spring element a polygonal cam having flat faces and set in a countersunk recess in a side groove and having its operating axis 20 projected through the inner side of the sash frame substantially at right angles thereto and provided with an operating element substantially as described.

In testimony whereof I affix my signature.

JESSE L. CARRIGAN.
